(57) **CLAIM**

The ornamental design for a quick release latch handle as shown and described.

DESCRIPTION

FIG. 1 is a right front perspective view of a quick release latch handle showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is bottom view thereof.

The dash-dash broken lines in the figures depict portions of the quick release latch handle that form no part of the claimed design. The dash-dot-dash broken lines in FIGS. 1, 3, 6, and 7 illustrate a boundary that does not correspond to or depict any particular feature of the claimed design and forms no part of the claimed design.
